US0D1012930S

(12) **United States Design Patent** (10) **Patent No.:** **US D1,012,930 S**
(45) **Date of Patent:** **** Jan. 30, 2024**

(54) **MONITOR**

(71) Applicant: **Samsung Electronics Co., Ltd.**, Suwon-si (KR)

(72) Inventors: **Minjoon Jung**, Suwon-si (KR); **Pilkwon Jung**, Suwon-si (KR); **Taeyeon Won**, Suwon-si (KR)

(73) Assignee: **SAMSUNG ELECTRONICS CO., LTD.**, Gyeonggi-Do (KR)

(**) Term: **15 Years**

(21) Appl. No.: **29/831,461**

(22) Filed: **Mar. 21, 2022**

(30) **Foreign Application Priority Data**

Sep. 27, 2021 (KR) 30-2021-0045718

(51) **LOC (14) Cl.** **14-02**

(52) **U.S. Cl.**

USPC **D14/371**

(57) **CLAIM**

The ornamental design for a monitor, as shown and described.

DESCRIPTION

FIG. 1 is a front perspective view of a monitor, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines illustrating portions of the monitor form no part of the claimed design.

1 Claim, 8 Drawing Sheets
